The Mitchel-Tyler Company, Hagerstown,
Md., a corporation of Maryland

Application November 27, 1943, Serial No. 511,977

9 Claims. (Cl. 46—80)

1

This invention relates to toy aircraft and more particularly to a retractable wing glider of the catapult launched type.

Retractable wing gliders which are launched with a catapult were originally designed to permit high launching speeds resulting in the attainment of greater heights and better gliding distances. Such gliders in general fall into two categories; those in which the wings merely pivot rearwardly in a single plane and those in which the wings not only pivot rearwardly but also downwardly to lie in planes parallel to the vertical plane of the fuselage. Of the two, the first mentioned type has the advantage of being easy and inexpensive to construct but has also the disadvantage of offering too little wing surface to the air during launching, resulting in loss of height due to premature return of the wings to extended gliding position. In the second type mentioned above, this difficulty is avoided since the flat surfaces of the wings rather than their leading edges are exposed to the air currents in launching. This results in the attainment of better height and in generally more satisfactory operation. However, due to the complexity of the movement involved in displacing the wings from gliding position to a retracted position flat against the fuselage, this type of glider has always been more costly to construct, involving complex pivotal mountings, springs, hinges, etc., all incidentally contributing undesirable weight.

It is therefore an object of this invention to overcome the foregoing disadvantages and to provide a toy airplane glider of simple and light weight construction, the wings of which may be retracted from gliding position to a launching position flat against the fuselage and yet will automatically return, in flight, to a predetermined gliding position resulting in long glides from great heights.

According to this invention it is contemplated that the wings be held against relative movement to facilitate catapult launching and that while retracted and so held the wings will serve to hold in position for delayed discharge an object such as a simulated bomb.

More specifically it is an object of this invention to provide a retractable wing arrangement in which a single elastic band functions to support and position the wings in flight, to return the wings from retracted position, and as a point of pivot for movement of the wings to and from retracted position.

Other objects and advantages of this invention will be apparent from a consideration of the fol-

2

lowing detailed description of a preferred embodiment thereof in connection with the annexed drawings, wherein:

Figure 1 is a perspective view of an airplane glider constructed according to this invention, illustrating the manner of launching the same with the main wings fully retracted;

Figure 2 is a top plan view thereof with the main wings in gliding position;

Figure 3 is a top plan view similar to Figure 2 with the main wings shown in retracted or launching position;

Figure 4 is a view in rear elevation of the tail wing assembly of the airplane glider shown in Figures 1, 2 and 3;

Figure 5 is a view in side elevation of the airplane glider of Figure 2 with the main wings shown in gliding position;

Figure 6 is a view in section taken on line 6—6 of Figure 3;

Figure 7 is a view in section taken from behind the main wings illustrating the initial movement in retracting them from the Figure 5 to the Figure 6 position; and

Figure 8 is a view in detail of the device used in aligning the main wings in retracted position.

Referring now in greater detail to the illustrations, the airplane glider is made up principally of a flat, vertically disposed body or fuselage 10, main wings 11 and a tail wing assembly 12.

The fuselage 10 is provided with a notched nose piece 13 which fits over its leading end and is fastened thereto by brads 14 or the like. Since the vertical height of nose piece 13 is greater than the corresponding vertical dimension of the fuselage, the resulting projecting portion 15 of the former is conveniently used to receive the elastic band 16 of the launching catapult as can be seen in Figures 1 and 6. The nose piece 13 also functions as a weight to depress the nose of the glider in flight so that the main wings will be in best position to afford the maximum lifting effect from the forward motion of the glider. To this end, nose piece 13 may be made of heavier material than the fuselage so as to afford the proper concentration of weight forward of the main wings. The fuselage 10 is customarily made of balsa or other like wood of sufficient strength but little weight.

The tail wing assembly 12 may be made of cardboard or like material as a unitary construction. The blank may be folded centrally at 17, see Figure 4, and the resulting upstanding portions fastened over the fuselage by staples 18 or the like. The remaining ends are then fold-

ed at right angles to define tail wings 19. To hold the tail wings 19 in a plane normal to the plane of the fuselage 10, a reinforcing strip 20 may be passed through slits cut in each tail wing 19 and under the resulting straps 21 to overlie the upper surfaces of each wing as can be seen in Figures 3, 4 and 5. Reinforcing strip 20 may be made of any material of sufficient rigidity to maintain tail wings 19 in position under conditions of flight.

Each main wing 11 is attached at its base to a rectangular block 22 of a length about equal to the chordwise width of the wing, of a height equal to about half the height of the fuselage and of a width which can best be determined by noting the proportions in Figure 7. Each block 22 is notched at each end at 23 and 24. A continuous elastic band 25 is passed around three sides of each block 22, the fourth sides resting against the fuselage, a slot 26 being provided in the fuselage to permit the band to pass therethrough and thus connect the blocks and urge them toward one another and against opposite sides of the fuselage as can best be seen in Figure 2. By this arrangement, a single elastic band serves to hold resiliently, in flying position, both of the main wings. It is apparent that by beveling the sides of the blocks which rest against fuselage 10, it is possible to dispose the wings 11 in any flying position; since the elastic band will always draw those sides of the blocks into tight engagement with the fuselage and the angle which the top of each block makes with the fuselage will also, of necessity be the wing angle.

It will be noted that slot 26 is about equal in length to the distance between the bottoms of the notches 23 and 24 in blocks 22 so that the band passes straight through the fuselage to connect the two blocks at their ends. It has been found that if the distance between the bottoms of notches 23 and 24 is equal to or possibly slightly greater than the length of slot 26, proper positioning of wings 11 for flight results.

To retract the wings to launching position they are first bent down to the full line position of Figure 7 and then pivoted in an anti-clockwise direction as indicated in Figure 6 to assume the position illustrated in Figures 3 and 6. In view of the fact that wings 11 are pivoted rearwardly, there is a tendency for the portion of band 25 connecting notches 23 to move in slot 26 toward the portion thereof connecting notches 24. If this were to happen the band would be merely twisted helically about $\frac{1}{4}$ turn and its thrust would be hardly sufficient to restore the wings 11 to gliding position. Therefore, to prevent this tendency, auxiliary angularly disposed notches 27 and 28 are provided at opposite ends of slot 26, see Figure 6. These notches receive the portions of the band 25 connecting opposite ends of blocks 22 and prevent them from moving toward one another. As a result, these portions of band 25 are greatly stressed when the wings are retracted, see Figures 3 and 6, so that the wings 11 are strongly urged to pivot in a clockwise direction as viewed in Figure 6 to resume the position of Figures 2 and 5.

With the wings 11 fully retracted, launching is effected by pressing the wings toward one another with the thumb and forefinger of one hand, the other hand being used to hold the catapult, see Figure 1. The glider is thus projected into the air and will assume gliding position when

the air pressure on wings 11 is no longer sufficient to overcome the thrust of band 25.

It can be seen that because of the tendency of wings 11 to pivot in a clockwise direction as viewed in Figure 6, difficulty might be experienced in preventing the wings from slipping out of the grip of the operator during launching or rotating in a clockwise direction under stress of the elastic band immediately after the glider is launched. According to the present invention this difficulty is obviated by guide members or projections 29 which extend laterally from opposite sides of the fuselage near the tail assembly 12. Wings 11 are provided with apertures at 30 which register with projections 29 when the wings are retracted so that the wings are prevented from pivoting away from the Figure 6 position so long as they are held together manually. After launching the wings are held together during upward flight by the pressure of the air on their flat surfaces. As a matter of construction, projections 29 may be integral with a metal blank of the type shown in Figure 8. A narrow slit is cut lengthwise in the fuselage 10 and flat portion 31 of the blank, about equal in width to the thickness of the fuselage, is inserted therein with its long axis parallel to the long axis of the fuselage. Tabs 32 are then bent down against opposite sides of the fuselage to hold the blank in position with projecting portions 29 extending outwardly from the fuselage to act as a guide for the wings.

In Figures 1, 2, 3 and 6 there is shown a simulated bomb 33 hanging from one of the projections 29. This device is simply a weight 34 and a loop member 35 for suspending the weight from a projection 29. The weight may conveniently consist of a double thickness of the loop material. Both may be made of cardboard.

When the glider is to be used to simulate bombing one or more simulated bombs 33 are suspended from projections 29 before the wings are retracted to launching position. Of course, when the wings are retracted, the simulated bomb is held against falling and so will be carried by the glider during the initial portion of its flight. When, however, the wings return to gliding position there is nothing to keep bomb loop 35 from sliding off of projection 29 under the influence of its weight 34. This will cause the bomb to fall some distance from the place at which the glider was launched and is realistic enough to considerably augment the amusement afforded by the glider.

Of course, instead of a simulated bomb a small parachute or other device may be held by projection 29 and realistically released when the wings spring to gliding position.

In the accompanying drawings, there is shown a preferred embodiment of the invention and the application thereof. These drawings and the foregoing specification and description are not intended to be exhaustive nor limiting of the invention, but on the contrary are intended with a view to best explaining the invention and principles thereof and the best manner of embodying the same, and it is intended to enable others skilled in the art to adapt and modify the invention and to construct it in such various forms as may be best adapted for the requirements of any particular condition.

What is claimed is:

1. A toy airplane glider comprising a body, wings extending on opposite sides of said body and resilient means connecting the bases of the

wings through the body at spaced points, said means constituting the sole connection of said wings to the body and to each other whereby the wings are resiliently held in gliding position but may be folded to lie flat against the body for launching.

2. A toy airplane glider comprising a body, wings extending on opposite sides of said body, a block on the base of each wing adapted to rest against said body to position the wing for gliding, and resilient means connecting the blocks through the body at spaced points, said means constituting the sole connection of said wings to the body and to each other whereby the wings are resiliently held in gliding position but may be folded to lie flat against the body for launching.

3. A toy airplane glider comprising a body, wings extending on opposite sides of said body, a block on the base of each wing adapted to rest against said body to position the wing for gliding, said body having a longitudinal slot therein at the wing zone, an elastic band passing around said blocks and connecting the respective ends of each through the longitudinal slot to bias said blocks against opposite sides of said body portion to hold the wings in gliding position, and means for holding the portions of the band connecting the respective ends of said blocks against movement toward one another, whereby the wings may be folded downwardly and pivoted rearwardly to lie in planes substantially parallel to the body portion for catapult launching while the stored energy in said elastic band will restore the wings to gliding position when air pressure on said wings is reduced.

4. A toy airplane glider comprising a body, wings extending on opposite sides of said body, a block on the base of each wing adapted to rest against said body to position the wing for gliding, said body having a longitudinal slot therein at the wing zone, and an elastic band passing around said blocks and connecting the respective ends of each through the longitudinal slot to bias said blocks against opposite sides of said body to hold the wings in gliding position, a downwardly extending notch in said body at the front end of the longitudinal slot, an upwardly extending notch in said body at the rear end of the longitudinal slot to hold the portions of the band connecting the respective ends of said blocks against movement toward one another, whereby the wings may be folded downwardly and pivoted rearwardly to lie in planes substantially parallel to the body portion for catapult launching while the stored energy in said elastic band will restore the wings to gliding position when air pressure on said wings is reduced.

5. A toy airplane glider comprising a flat, vertically extending body, wings mounted on the forward portion of said body for movement from a gliding position in a plane substantially normal to the plane of the body to a launching position parallel to the plane of the body, means normally biasing said wings to gliding position, said means constituting the sole connection of said wings to the body and to each other, said wings having slots therein adjacent their ends, and means pro-

jecting laterally from the said body in a position to register with said slots when the wings are in launching position, whereby the wings are readily held against their normal bias during launching and upward flight.

6. A toy airplane glider as claimed in claim 5 further comprising a simulated bomb having a loop, said loop being passed over one of the means projecting laterally from said body whereby when the wings are retracted the simulated bomb will be held for flight with the glider while when the wings are extended, the simulated bomb will fall by gravity.

7. A toy airplane glider comprising a body, wings extending on opposite sides of said body, a block on the base of each wing adapted to rest against said body to position the wings for gliding, resilient means connecting the blocks through the body at spaced points, said means constituting the sole connection of said wings to the body and to each other, and means projecting laterally from said body, said wings having slots therein adjacent their ends for cooperation with the means projecting laterally from the body when the wings are in launching position, whereby the wings are held against the action of the resilient means tending to restore them to gliding position.

8. A toy airplane glider as claimed in claim 7 further comprising a simulated bomb having a loop, said loop being passed over one of the means projecting laterally from said body whereby when the wings are retracted the simulated bomb will be held for flight with the glider while when the wings are extended, the simulated bomb will fall by gravity.

9. A toy airplane glider comprising a body, wings extending on opposite sides of said body, a block on the base of each wing adapted to rest against said body to position the wing for gliding, said body having a longitudinal slot therein at the wing zone, and an elastic band passing around said blocks and connecting the respective ends of each through the longitudinal slot to bias said blocks against opposite sides of said body to hold the wings in gliding position, a downwardly extending notch in said body at the front end of the longitudinal slot, an upwardly extending notch in said body at the rear end of the longitudinal slot, whereby said slots relieve excessive strain on the elastic band when the wings are fully pivoted rearwardly and at the same time serve to guide and propel the elastic band to a normal position in which the wings are in gliding position.
